[57] CLAIM

The ornamental design for a Santa's boot track template, as shown and described.

DESCRIPTION

FIG. 1 is a front perspective view of a Santa's boot track template showing my new design, the template shown in a position of use;

FIG. 2 is a right side elevational view thereof, the left side being identical;

FIG. 3 is a front elevational view thereof, the rear being identical; and,

FIG. 4 is a top plan view thereof, the bottom plan being identical.
